UNITED STATES PATENT OFFICE.

THOMAS KOCHKA, OF NEW YORK, N. Y.

TOY BOWLING-ALLEY.

SPECIFICATION forming part of Letters Patent No. 621,967, dated March 28, 1899.

Application filed January 17, 1899. Serial No. 702,402. (No model.)

To all whom it may concern:

Be it known that I, THOMAS KOCHKA, a citizen of the United States, residing at New York city, county and State of New York, have invented new and useful Improvements 5 in Toy Bowling-Alleys, of which the following is a specification.

This invention relates to a toy bowling-alley of the class in which the pins are connected 10 by strings to a common slide or cross-head, so that they may be collectively set up.

The invention consists in means for adjustably connecting the strings to such slide in order to compensate for slack, in improved 15 means for swiveling the propeller to the game-board, and in other features of improvement, all as hereinafter more fully pointed out.

In the accompanying drawings, Figure 1 is a plan of my improved toy bowling-alley; Fig. 2, a vertical longitudinal section on line 2 2, Fig. 1; Fig. 3, a bottom view with the parts n n' partly broken away; Fig. 4, a section on line 4 4, Fig. 3; Fig. 5, an end view, partly in section, of the game-board; and Figs. 6 and 25 7, details of the split bearing i j.

The letter a represents the game-board or table, perforated at a' beneath each of the pins b. Strings c, attached to the lower ends of the pins, pass through these perforations 30 and extend beneath transverse rollers d to a common cross-head e, to which they are connected. The cross-head is operated by a handle e', surrounded by a spring e''. By drawing the handle of the cross-head forward a pull 35 will be exerted upon all of the strings c to set up the pins b. The releasing of the handle will cause the spring e'' to draw the cross-head inward, so that the strings c are slackened and the righted pins may be bowled over.

40 In course of time the strings c are apt to unevenly stretch, so that if compensating means are not provided the movement of the plunger will set up some but not all of the pins. To overcome this difficulty, I adjustably attach each of the strings c to the cross-head e, so that the length of every string may be separately regulated.

45 The adjusting means consist of longitudinally-perforated screws f, tapped into transverse openings of cross-head e and adapted 50 to receive the strings c, which pass entirely

through such screws and have knotted ends back of the screws. Thus a turn of the screw will lengthen or shorten the working length of each string without, however, twisting 55 the same.

The propeller for projecting the ball against the pins is swiveled to the game-board, so that it may be pointed in different directions. It consists of a scoop or ball-seat g, secured 60 to a pair of parallel bars g', surrounded by springs g'' and carrying a handle g''. The bars g' are surrounded between the springs and handle by a swivel-plate h, having upper and lower pivots h'. These pivots engage 65 the perforations i' j' of a split bearing i j, embracing the swivel-plate and fitted within an opening formed in the front rim a'' of game-board a. The lower bearing j has flanged edges j'', Fig. 7, to grasp the edge of 70 the opening, while the upper bearing i has corresponding flanges i'' and a flanged perforated top i''', adapted for the reception of the fastening-screws. By means of this bearing the propeller may be quickly and firmly 75 secured to the game-board in such a manner that it may be freely pointed in any direction.

The legs k of the alley are pivoted and may be folded flat against the lower side of table a. To each leg is pivoted a diagonal brace 80 k', provided at its free end with a pin k'', guided within a slot l' of a longitudinal rail l, that extends underneath board a at a short distance from its longitudinal edge. Stays m, pivoted on vertical pivots to a supporting-block m', are adapted to engage the inner edges of the braces k' when the legs are swung down, and thus lock the latter in their open position. When the legs are folded, the stays m are swung bodily over the lower sides 85 90 of the same to lock them in their closed position against table a.

The operating parts of the alley are protected by a bottom plate n and a lid n', hinged at n'' and of a width to extend between the longitudinal rails l.

What I claim is—

1. In a toy bowling-alley, the combination of a perforated game-board, with pins, a tapped movable cross-head, longitudinally-perforated screws engaging the cross-head, and strings that are connected to the pins and

pass longitudinally through the perforated screws, said strings having knotted ends back of the screws, substantially as specified.

2. In a toy bowling-alley, the combination 5 of a game-board having a notched rim, with upper and lower bearings having flanges that grasp the edges of the rim-notch, means for securing the upper bearing to the rim, a perforated swivel-plate turning in the bearings, 10 and a propeller embraced by the swivel-plate, substantially as specified.

3. In a toy bowling-alley, the combination 15 of a game-board with pivoted legs, diagonal

braces pivoted thereto and having laterally-extending pins, slotted guide-rails adapted 15 to receive said pins, and stays turning on vertical pivots and adapted to engage the inner edges of the diagonal braces when the legs are open, and to be projected over the lower sides of the legs when the latter are folded, 20 substantially as specified.

THOMAS KOCHKA.
